FILM STRIP VIEWER

Alan Kellock and Edward S. Cobb, Freeport, and

David W. Leake, Babylon, N. Y.

Application June 1, 1956, Serial No. 41,723

Term of patent 7 years
(Cl. D61—1)

The broken line showing of a film strip is for illustrative purposes only.

We claim:

The ornamental design for a film strip viewer, as shown and described.
